UNITED STATES PATENT OFFICE.

JOHN WARWICK AND WALTER C. WESTAWAY, OF BELOIT, WISCONSIN.

WINDMILL.

SPECIFICATION forming part of Letters Patent No. 254,075, dated February 21, 1882.

Application filed July 30, 1881. (No model.)

To all whom it may concern:

Be it known that we, JOHN WARWICK and WALTER C. WESTAWAY, citizens of the United States, of Beloit, in the county of Rock and State of Wisconsin, have invented a new and valuable Improvement in Windmills; and we do hereby declare that the following is a full, clear, and exact description of the construction and operation of the same, reference being had to the annexed drawing, making a part of this specification, and to the letters and figures of reference marked thereon.

The figure of the drawing is a representation of a side elevation of our invention with a portion of the top broken away.

This invention relates to improvements in windmills; and it consists in a combined pumping and geared windmill, constructed and arranged as hereinafter set forth and claimed.

In the annexed drawing, the letter *a* represents the frame of a windmill having the stationary cross-bar *b*, which supports the pivot-bearing *c*. On this bearing rests the stem *d* of the windmill-pivot *e*, which carries the fan and tail. Passing up through the bar *b*, bearing *c*, and stem *d* is a hollow shaft, *f*, which is stepped below in a bearing, *g*, situated on an adjustable cross-bar, *h*, and has a bearing in an arm, *k*, near the top of the pivot *e*. Keyed to this shaft is a bevel-gear wheel, *l*, which engages another wheel, *m*, on the inner end of the fan-shaft. The shaft *f* can be connected in any suitable way with any mechanism which

it is desired to operate. The bar *h* is vertically adjustable by a cord, *n*, and pulley, and by this means the shaft *f* can be raised or lowered and the wheel *l* be thrown in or out of gear.

Passing up through the shaft *f* is the pump-rod *q*, which has a bearing in a bracket, *r*, above the pivot, and is connected to the wheel *m* by the pitman *s* and pin *l'*. When desired, this rod *q* can be disconnected either from the fan above or the pump below.

The construction described furnishes a mill which can be used for pumping and for driving machinery, or which can be used for either alone, as may be desired.

Having described our invention, what we claim, and desire to secure by Letters Patent, is—

In a windmill, the combination, with the frame *a*, having the rigid cross-bar *b*, provided with the bearing *c*, and the pivoted adjustable cross-bar *h*, provided with the bearing *g*, of the stem *d*, hollow shaft *f*, rod *q*, bracket *r*, gearing *l m*, and pitman *s*, substantially as and for the purposes specified.

In testimony that we claim the above we have hereunto subscribed our names in the presence of two witnesses.

JOHN WARWICK.

WALTER C. WESTAWAY.
